UNITED STATES PATENT OFFICE.

THEODOR J. WILLMA, OF MILWAUKEE, WISCONSIN, ASSIGNOR OF ONE-EIGHTH TO PETER WARAXA AND ONE-EIGHTH TO JOHN T. WILLMA, BOTH OF MILWAUKEE, WISCONSIN.

TOE-STEAMER.

1,348,340.

Specification of Letters Patent.

Patented Aug. 3, 1920.

Application filed May 5, 1919. Serial No. 294,723.

To all whom it may concern:

Be it known that I, THEODOR J. WILLMA, a citizen of the United States, and resident of Milwaukee, in the county of Milwaukee,

5 and State of Wisconsin, have invented new and useful Improvements in Toe-Steamers, of which the following is a description, reference being had to the accompanying drawings, which are a part of this specification.

10 The invention relates to a toe steamer for steaming the box of the toe preparatory to drawing the leather over the box and lasting it in place.

Heretofore toe steamers have been used 15 in the form of steam jets but these are unsatisfactory because much steam is wasted and because there is a liability of injuring the leather by contact with the steam. The present construction overcomes these difficulties by providing a steam box from which the steam is allowed to escape only when it is needed and by providing means for localizing the application of the steam to only that portion of the shoe where it is needed.

25 The invention further consists in the several features hereinafter set forth and more particularly defined by claims at the conclusion hereof.

In the drawings: Figure 1 is a plan view 30 of the device embodying the invention; Fig. 2 is an end view thereof, parts being broken away and parts being shown in section; Fig. 3 is a front side view of the device, parts being broken away; Fig. 4 is a detail view of the tip steamer, parts being broken away and parts being shown in section; Fig. 5 is a detail view of the top of the steam box; Fig. 6 is a section taken on the line 6—6 of Fig. 3; Fig. 7 is a detail bottom view of one of the valves in the steam box; Fig. 8 is a detail plan view of the guard plates showing the toe end of the shoe inserted between them in inverted position.

40 The steam box 8 is made up of a bottom section 9 and a top section 10 carrying flanges 11 overlapping the top edge of the section 9, the sections being secured together by clamps consisting of wire loops 12 secured to cam lever locks 13 on the section 50 9 and lockingly engaging screws or projections 14 on the section 10. Steam is supplied through a pipe 7 and returned through a pipe 6. On the top of the box there are openings 15 and 16 for each

steamer with semi-circular flanges 17 and 55 straight flanges 18 adjacent each set of openings which serve to detachably secure the steaming devices thereto.

Within the box adjacent each set of openings 15 and 16 are spring hinged plates 19 60 forming valves for the steaming devices consisting of a steamer for the top portion of the box of the shoe and one for tip of the toe, said devices being herein termed a box steamer and a tip steamer and both 65 coöperating to steam the toe of the shoe preparatory to drawing the leather over the box and lasting it in place.

The box steamer consists of a receptacle 20, adjustable toe clamping and guard 70 means, and means for automatically opening the valve or plate 19 associated therewith.

The receptacle 20 is semi-cylindrical in form with a front wall 21 having a toe receiving recess 22 therein. Flanges 23 and 24 are provided on the bottom of the receptacle to engage beneath the flanges 17 and 18 and said receptacle is held in this position by means of pivoted latches 25 on 75 the upper section 9. A tight fit between the receptacle 20 and the top section of the box is thus provided and the receptacle may be removed when desired by turning down the latches 24 and sliding the flanges on the 80 receptacle out of engagement with those on the steam box.

Arms 26 are pivotally mounted intermediate their ends upon the sides of the chute 20 and carry a shoe rest 27 at their outer ends and at their inner ends are operatively connected by links 28 to cranked arms 29 secured to a shaft 30 journaled in the receptacle and having a centrally disposed integral arm 31 pivotally connected to an eyed 90 member 32 on the valve 19 and projecting upwardly through the opening 15. With this construction when the shoe is laid in the rest 27 in inverted position with the uncovered box portion of the toe projecting 100 into the receptacle and the rest pressed downwardly, then the valve 19 below the receptacle will be opened inwardly through the movement of the arms 26, links 28 and cranked shaft 30, and steam will pass from 105 the steam box up the receptacle against the shoe.

In order to hold the shoe in a fixed posi-

tion during this steaming operation and also to prevent the escape of steam from the receptacle around the sides of the toe of the shoe, plates 33 are pivotally mounted intermediate their ends upon the wall 21 in spaced relation to receive the toe of the shoe between them and are automatically moved to clamping and guarding position on the opening of the valve 19. This movement is accomplished by links 34 pivotally connecting the inner ends of the arms 26 to levers 35 pivotally mounted on the receptacle, which levers are pivotally connected by yielding links 36 to the ends 37 of levers 38 pivotally connected together at their inner ends 39 and links 40 pivotally connected at one of their ends to the pivotal connections of the levers 38 and links 36 and pivotally connected at their other ends to the lower ends of the plates 33. Springs 26 normally hold the arms 26 and rest 27 in their upper position, shown in Fig. 2. Each link 36 is made yielding by forming it of two parts 41 and 42 slidably movable with respect to each other and having a spring 43 mounted on the part 41 yieldingly engaging the lower end of the part 42. This connection provides a lost motion connection between the arms 26 and the plates 33 so that said plates are capable of an independent movement to yieldingly clamp the shoe between them on the downward movement of the arms 26. As the plates 33 are disposed adjacent the recess 22 in the wall 21 when the shoe is placed in position, the inward movement of the plates against the sides of the shoe will close up the sides of the recess not occupied by the shoe and thus prevent the steam from injuring the upper leather.

The tip steamer consists of a housing 44 having a steam conduit 45 and a long narrow opening or orifice 46, said housing having bottom flanges 47 and 48 engaging beneath the flanges 17 and 18 and detachably secured therein by latches 49 on the upper section. To properly position the shoe over the orifice 46 and prevent its end being moved therebeyond and to prevent steam injuring the leather, guard plates 50 are hingedly secured to the sides of the housing adjacent the orifice and have outwardly curved shoe engaging portions 51 to limit the movement of the shoe.

The plates are adjustably secured in position by means of springs 52 holding the plates against segmental toothed latches 53 pivotally mounted on top of the housing. The adjustment of the plates with respect to each other provides for shoes of different sizes and widths.

The valve 19 for the tip steamer is actuated in a manner similar to that previously described for the other valve. A rest 54 is carried by arms 55 pivotally

mounted on the housing 44 and connected by links 56 connected to cranked arms 57 on a shaft 58 connected to the valve 19 in a manner identical with that for the previously described device. A spring 59 normally holds the arms 55 and rest 54 in upper position. With this construction when the shoe is laid in the rest 54 in inverted position with the sides of the box portion engaging the stop plates 50, the uncovered tip will be disposed over the orifice and the leather disposed beneath the orifice and protected at the side by the plates, and when the rest is pressed downwardly the valve 19 opens inwardly to permit steam to pass from the box through the conduit 45 and orifice 46 against the shoe.

From the foregoing description it will be noted that the steam is not used until actually needed and the shoe is in position to receive it and that the steam is directed against the part to be steamed and is prevented from injuring the upper leather.

What I claim as new and desire to secure by Letters Patent is:

1. In a toe steaming device, the combination, with a steam box provided with an opening, of a movable shoe rest, and a valve at the opening and operatively connected to said rest and controlling said opening.

2. In a toe steaming device, the combination, with a steam box provided with an opening, of a movable shoe rest, a valve at the opening and operatively connected to said rest and controlling said opening, and means for positioning the toe of the shoe adjacent the opening and preventing steam injuring the upper.

3. In a toe steaming device, the combination, with a steam box provided with an opening, of a valve at the opening and controlling the passage of steam therethrough, and means for supporting a shoe adjacent said opening and operating said valve.

4. In a toe steaming device, the combination, with a steam box provided with an opening, a valve at the opening and controlling the flow of steam through said opening, shoe supporting means for moving the valve, and adjustable guard plates adjacent the opening.

5. In a toe steaming device, the combination, with a steam box provided with an opening, a valve controlling the flow of steam through said opening, a receptacle adjacent the opening, shoe clamping and guarding plates on said receptacle, and shoe supporting means operatively connected to said valve and said plates for the purpose described.

6. In a toe steaming device, the combination, with a steam box provided with an opening, of a shoe rest, movable supporting arms for said rest, a valve within the box beneath said opening, and a connection be-

tween said arms and valve for opening said valve on a depression of said rest, and means for normally closing said valve.

7. In a toe steaming device, the combination, with a steam box provided with an opening, of a valve within the box beneath the opening, shoe supporting means operating said valve, a receptacle adjacent the opening, and clamping and guarding plates 10 operatively connected with said valve operating means and yieldingly engaging the shoe.

8. In a toe steaming device, the combination, with a steam box provided with an

opening, a valve at the opening and controlling the flow of steam through said opening, shoe supporting means for moving said valve, and yieldingly mounted guard members engageable with the shoe to prevent steam injuring the upper. 15

In testimony whereof I affix my signature, 20 in presence of two witnesses.

THEODOR J. WILLMA.
